UNITED STATES PATENT OFFICE.

WILLIAM E. KIMMELL, OF SEYMORE, INDIANA.

DESIGN FOR A DISPLAY-FORM.

SPECIFICATION forming part of Design No. 32,978, dated July 24, 1900.

Application filed June 25, 1900. Serial No. 21,576. Term of patent 7 years.

To all whom it may concern:

Be it known that I, WILLIAM E. KIMMELL, a citizen of the United States, residing at Seymour, in the county of Jackson and State of Indiana, have invented a new and original Design for a Display-Form, of which the following is a specification.

This invention relates to a new and original design for a display-form; and the essential feature resides in the formation of an under flat side and an upper side, which gradually slopes upwardly from one end and a portion of one side in convex contour toward an eccentric apex with a flat face, and from said apex toward the opposite end and a portion of the sides the upper surface takes an abrupt concave configuration.

In the drawings, Figure 1 is a plan view of a display-form embodying the features of the design. Fig. 2 is a transverse vertical section of the same on the line 2 2, Fig. 1. Fig. 3 is a longitudinal vertical section of the same on the line 3 3, Fig. 1.

Similar numerals of reference are employed to indicate corresponding parts in the several views.

The numeral 1 designates a flat under side, and 2 and 3 straight ends, which are parallel and connected by one curved side edge 4 of convex form and an opposite straight side edge 5, which takes a converging sweep toward the end 2. The greater portion of the upper surface 6 is convex and slopes upwardly from the end 3 and the side edges to an eccentric apex 7, having a flat face 8, and from said apex the upper surface has an abrupt concave trend and contour toward the end 2 and the adjacent portions of the side edges.

Having thus described the invention, what is claimed as new is—

The design for a display-form, herein shown and described.

In testimony that I claim the foregoing as my own I have hereto affixed my signature in the presence of two witnesses.

WILLIAM E. KIMMELL.
